UNITED STATES PATENT OFFICE.

ALONZO G. KINYON AND JOHN R. SAUNDERS, OF HORNELLSVILLE,
NEW YORK.

ROTARY ENGINE.

No. 821,647.

Specification of Letters Patent.

Patented May 29, 1906.

Application filed September 13, 1905. Serial No. 278,242.

To all whom it may concern:

Be it known that we, ALONZO G. KINYON and JOHN R. SAUNDERS, citizens of the United States, residing at Hornellsville, in the county of Steuben and State of New York, have invented certain new and useful Improvements in Rotary Engines, of which the following is a specification.

This invention relates to improvements in steam or other fluid pressure engines of the rotary type; and one object of our improvements is to provide the engine with a rotating valve and an adjustable seat for the valve, whereby the admission-ports may be changed to vary the point of cut-off—in other words, to provide the engine with variable admission-ports—while the valve travel remains constant for any given speed of the engine.

A further object is to provide means for shifting the seat, not only to vary the cut-off, but also to reverse the engine; and a final object is to provide means for balancing all working parts of the engine and especially the rotating abutment-cylinders for the pistons.

We attain our objects by means of the arrangement and construction of the several parts of the engine and valve, as illustrated in the accompanying drawings, in which—

Figure 1 represents a side elevation of a double-cylinder engine embodying our improvements, one-half of the engine being shown in longitudinal section; Fig. 2, an end elevation of the same; Fig. 3, a vertical transverse section on the line xx in Fig. 1; Fig. 4, a detail showing a section through one of the balance-chambers on the line yy in Fig. 1; Fig. 5, a side elevation of the valve-seat removed; Fig. 6, a transverse section of the same on line zz in Fig. 5; Figs. 7 and 8, transverse and longitudinal sections, respectively, of the valve; Fig. 9, an end view of one of the abutment-cylinders; Fig. 10, a vertical longitudinal section of the same; Fig. 11, one of the packing-rings for the valve-seat and abutment-cylinders, and Fig. 12 side and end views of one of the packing-rollers for the wing-pistons.

Like numerals designate like parts in the several views.

In order to avoid dead-centers and impart a constant driving force to the main shaft, we provide the engine with double cylinders,

in which rotate wing-pistons set in diametrically opposite positions upon the shaft. As shown in Fig. 1, these cylinders 1 are formed together in one casting, their outer ends being closed by the heads 2, said heads being provided with eccentric cylindrical extensions which form balance-chambers for the abutment-cylinders 8 outside the bearings for said cylinders. Between the main cylinders at 3 similar balance-chambers are formed, said chambers being separated from one another by diaphragm 4. Projecting inwardly from the cylinder-heads and from each side of the diaphragm 4 are the bearings 6 for the main shaft 5. Between these bearings in each cylinder the wing-pistons 7 are located, with their hubs keyed to the shaft 5. These pistons pass through slots provided therefor in the abutment-cylinders and rotate in engagement with the sides and circumferential walls of the main cylinders, the sides and outer ends of the pistons being provided with grooves to receive spring-pressed packing-strips, as indicated by the broken lines in Fig. 1 and at 31 in Fig. 3. In order to pack the joints where the wing-pistons pass out through the abutment-cylinders and to provide for the movements of the pistons relatively to said cylinders, we provide slotted rollers 10, the ends of which are journaled in bearings provided therefor in the inwardly-projecting bosses 11, formed on the abutment-cylinders, the sides of these bosses being curved to engage the sides of the rollers. The rollers have double packing-strips 12 in slots at each side of the pistons, which are held by suitable springs in contact with the sides of the bosses 11 and the pistons. In order to assemble the parts, the abutment-cylinders are made in halves, the two parts being fastened together after the pistons and rollers are in position by means of bolts passing through lugs 9, formed on the inner walls of said cylinders.

The inner and outer ends of the abutment-cylinders rotate in the eccentric balance-chambers formed between the cylinders and in the cylinder-heads, and these eccentric balance-chambers are made of sufficient depth to provide for the formation therein of grooves, whereby a counterbalancing steam-pressure may be admitted to the outer peripheries of the abutment-cylinders at oppo-

site sides to that on which the steam-pressure is applied in the main cylinders. To accomplish this counterbalancing effect, the grooves 13 in each chamber are made equal to one-half the width of the main cylinders, so that the combined pressure areas at the ends of the abutment-cylinders will equal the area of said cylinders exposed to pressure in the main cylinders. The grooves 13 are shallow and do not extend completely around the balance-chambers, the ends of the grooves terminating at points opposite the dead position of the pistons. The escape of steam past said ends is prevented by packing-strips at 17, which engage the peripheries of the abutment-cylinders. The abutment-cylinders are provided with spring-pressed packing-blocks 14 at points diametrically opposite the slots for the pistons, said packing-blocks engaging the grooves 13 and dividing them into pressure and exhaust chambers corresponding in extent to the pressure and exhaust chambers formed in the main cylinders as the pistons rotate. The ends of the grooves 13 are tapered off in order that the packing-blocks 14 may ride out of and into the grooves as the abutment-cylinders rotate.

At points adjacent to the ends of the grooves at one side of the balance-chambers 30 holes are tapped to receive nipples 18, from which pipes 19 pass around to the opposite side of the engine, said pipes being coupled into cross-pipes 20 and said cross-pipes connected at 21 to steam-passages 22, which lead 35 from the valve-chamber to the main cylinders. Near the other ends of the grooves 13 the balance-chambers are tapped to receive nipples 23, from which pipes 24 pass again to the opposite side of the engine and are connected by cross-pipes 25 to connections 26, leading into the passages 27, which lead from the valve-chamber to the main cylinders upon the opposite side of the engine from the passages 22.

From an inspection of Fig. 3 it will be seen that when steam is admitted to the cylinders in the direction indicated by the arrows the pressure of the live steam will be upon the right-hand side of the abutment-cylinders, thereby forcing the outer peripheries of said cylinders against the walls of the balance-chambers upon the left-hand side, tending to produce excessive friction as the abutment-cylinders rotate in contact therewith. By 55 means of our counterbalancing-grooves, however, this side pressure and friction is avoided, since live steam will pass through connections 26 and 25 to the pipes 24 and thence to the grooves 13 upon the left-hand side of the abutment-cylinders, the grooves at the opposite side being open to the exhaust by way of pipes 19 and connections 20 and 21 with the passage 22, which is the exhaust-passage as the engine is shown in this figure.

65 The packing-rings 15 at the ends of the

guide-cylinders and packing-rings 16, set in grooves in the periphery of the abutment-cylinders, prevent leakage of steam into or out of the counterbalancing-grooves, and the packing-strips 30 where the abutment-cylinders 70 contact with the walls of the main cylinders prevent leakage of steam from one side of the abutment-cylinders to the other.

Extending across the cylinders is a valve-chamber 35, cylindrical in form and containing a movable valve-seat cylinder 34, within which the cylindrical valve 41 is rotated by shaft 43. At each end the valve-seat is provided with port-openings 28 and with exhaust-grooves 29, which register with the passages 27 and 22, leading to the two cylinders. The exhaust-grooves are separated from the port-openings by longitudinal partitions 36 and 37, said partitions being provided with packing-strips 39 at their outer edges to insure steam-tight joints. In the outer periphery of the valve-chamber packing-rings 40 are also provided at each side of the exhaust-grooves and port-openings to insure steam-tight joints.

At 38 the valve-chamber is provided with stationary abutments, which project through the port-openings 28 in the valve-seat and engage the outer periphery of the valve 41. Packing-strips 49 prevent leakage of steam 95 past these abutments.

The valve at each end is provided with diametrically opposite ports 42 to register with the port-openings 28, around the outer edges of which ports are located packing-strips to 100 prevent the leakage of steam around the valve. These ports at the opposite ends of the valve are set quartering (see Figs. 7 and 8) in order that the steam may be admitted to the cylinders in accordance with the position of the pistons therein. The ends of the valve-chamber are closed by the heads 44 and 45, the latter head being provided with an extension to form an admission-chamber for the steam, which is conducted to the engine by the pipe 47. Packing-rings 48 are provided to furnish steam-tight joints between the ends of the valve and the heads 44 and 45. The steam after passing into the chamber 46 enters the hollow valve and by 105 way of ports 42 is delivered through the port-openings 28 in the valve-seat to the passages 27 or 22, according to the adjustment of said seat, the exhaust taking place by way of the grooves 29 and the passages 32 at the top of 110 the valve-chamber and passing away by the exhaust-pipe 33.

The valve-seat is mounted to turn in the valve-chamber, the rotary adjustment of the valve being attained by means of the worm 115 52, which engages teeth 53, formed upon the outer periphery of the seat, as shown in Figs. 5 and 6. The worm-shaft 50 passes out through a stuffing-box 51 and may be rotated by hand or automatically by a suitable gov-

ernor connection with the driving-shaft either to change the point of cut-off or to reverse the engine.

The valve-shaft is geared to the main shaft of the engine by gear-wheels proportioned two to one, said gear-wheels being indicated by broken lines in Figs. 1 and 2 at 55 and 54, respectively. The valve will therefore rotate in fixed relation to the revolving pistons and 10 at one-half their angular speed, the oppositely-disposed admission-ports 42 in the valve causing steam to be admitted to the cylinders for each revolution of the pistons. The reduced speed of the valve gives the 15 port-openings 42 a proportionately longer period of transit through the extent of the port-openings 28 in the valve-seat and when said port-openings are adjusted to their fullest extent will permit steam to follow the 20 pistons for full stroke. If it is desired to reduce the point of cut-off, so as to use the steam more or less expansively, the port-openings 28 may be contracted by shifting the valve-seat either to the right or left, according to how the engine is set to rotate.

In the position assumed for the several parts of the engine in Figs. 1 and 3 the steam after entering the valve 41 will pass out through ports 42 in the direction indicated 30 by the arrows and will continue to pass through the port-openings 28 in the valve-seat and into the passages 27 while each of the ports 42 is passing from the abutment 38 to the partition 36 or during practically the 35 full stroke of the piston, the exhaust taking place by way of passages 22 and grooves 29. If it is desired to cut off the admission of steam earlier, this may be accomplished by rotating the valve-seat to the right, thereby 40 causing partition 36 to approach the abutment 38. By continuing this left-to-right rotation the cut-off may be brought down to zero, and a still further rotation of the valve-seat will cause the partitions 36 and 37 to 45 pass the openings into the passages 27 and 22, respectively, after which steam will be admitted into the passages 22 and exhaust will take place from passages 27, thereby reversing the engine. As already stated, this 50 adjustment of the valve may be accomplished by hand, or the worm-shaft 50 may be under the control of a governor, as will readily be understood by those skilled in the art. If the worm-shaft is placed under the 55 control of a governor, it will be so rotated as to lengthen or shorten the point of cut-off as the load on the engine increases or decreases, respectively.

By reason of the disposition of the ports 42 in the valve said valve will be in balance as it rotates on its shaft within the valve-seat. The parts of the engine are therefore free running, and the friction loss inherent in this type of engines is reduced to a minimum, the 60 only friction being that of the packing strips

and rings where they rotate in contact with the bearing-surfaces and in the shaft-bearings.

By arranging the engine with two cylinders tandem the power from the pistons is transmitted directly to a common driving-shaft. Moreover, by reason of the piston construction herein shown there will be a balancing of the pressures upon the two pistons, so that the shaft will be acted upon at 75 all periods of a complete revolution by a practically constant force. This will be evident from the fact that when one of the pistons is passing its dead-point—that is to say, the space between the packing-strips 30 at 80 the top of the cylinder—the other piston will have its largest area exposed to the steam-pressure, and as the revolution continues the pressure area of the one piston will increase in the same proportion as the pressure area of 85 the other decreases until the second piston arrives at its dead position.

While we have shown and described our valve and its adjustable seat as applied to our particular form of rotary engine, we do 90 not wish it understood that we limit ourselves to such application of this part of our invention, inasmuch as they may also be applied to other forms of fluid-pressure engines.

What we claim as our invention, and desire to secure by Letters Patent, is—

1. The combination, in an engine, of a valve, a movable valve-seat provided with a port-opening, a stationary abutment in said opening, passages with which the port-opening registers leading to opposite ends of the engine-cylinder from opposite sides of said abutment, and means for shifting the seat to cause the ends of the port-opening to approach or recede from the abutment at either 100 side thereof to change the point of cut-off or reverse the flow of motive fluid in the engine.

2. The combination, in an engine, of a pair of cylinders placed tandem, oppositely-disposed pistons in the two cylinders, a valve-chamber extending across the cylinders, a movable valve-seat in said chamber provided with a port-opening opposite each cylinder, a stationary abutment in each of said openings, 110 passages with which the port-openings register leading to opposite ends of the respective engine-cylinders from opposite sides of said abutments, a valve having port-openings adapted to register with the port-openings in the valve-seat, said valve-ports being 115 so positioned as to admit the motive fluid to the respective cylinders at the beginning of each piston-stroke and means for shifting the valve-seat to cause the ends of the port-openings to approach or recede from the abutments at either side thereof to change the point of cut-off or reverse the flow of motive fluid in the engine.

3. The combination, in an engine, of a revoluble cylindrical valve, into which the mo- 130

- 5 tive fluid is delivered, a port or ports passing through the walls of the valve, a cylindrical seat within which the valve is mounted, a port-opening passing through said seat with which the valve port or ports register, a passage leading from said port-opening to one end of the engine-cylinder, a stationary abutment in the port-opening at one side of said passage, a groove in the outer periphery of the valve-seat opposite the port-opening, a passage leading from said groove to the other end of the engine-cylinder, an outlet for the exhaust in communication with said groove, and means for turning the valve-seat to change the point of cut-off.
- 10 4. The combination, in an engine, of a rotary cylindrical valve into which the motive fluid is delivered, a port or ports passing through the walls of the valve, a cylindrical seat within which the valve rotates, a port-opening passing through said seat with which the valve port or ports register, passages with which said port-opening registers leading to opposite ends of the engine-cylinder, a stationary abutment in the port-opening between said passages, a groove in the outer periphery of the valve-seat extending around from one end of the port-opening to the other, partitions between the groove and the port-opening, an outlet for the exhaust in communication with the groove at all times, and means for turning the valve-seat to change the point of cut-off or reverse the flow of motive fluid in the engine.
- 15 5. The combination, in an engine, of a pair of cylinders placed tandem, rotary pistons in the cylinders set diametrically opposite one another upon a driving-shaft, a valve-chamber extending across the cylinders, a movable cylindrical valve-seat in said chamber, a port-opening passing through the valve-seat opposite each cylinder, stationary abutments in the port-openings, passages leading to opposite ends of the cylinders from opposite sides of said abutments, grooves in the outer periphery of the valve-seat extending around from one end of the port-openings to the other, partitions between the grooves and the port-openings, exhaust-passages leading from said grooves to a common outlet, a cylindrical valve mounted on a shaft to rotate
- 20 within the valve-seat, diametrically opposite ports in the valve to register with each port-opening in the valve-seat, the ports at one end of the valve being set at an angle of 55 ninety degrees with respect to the ports at the other end, means for transmitting motion from the driving-shaft to the valve-shaft at one-half speed, and means for turning the valve-seat to change the point of cut-off or to 60 reverse the flow of motive fluid in the engine.
- 25 6. The combination, in a rotary engine, of a cylinder, a wing-piston and an abutment-cylinder rotating therein, balance-chambers at each side of the engine-cylinder inclosing the ends of the abutment-cylinder, and means for admitting the motive fluid to said chambers against the periphery of the abutment-cylinder upon the side opposite to that which receives the pressure in the main cylinder. 70
- 30 7. The combination, in a rotary engine, of a cylinder, a wing-piston and an abutment-cylinder rotating therein, admission and exhaust passages leading the motive fluid to and from the engine-cylinder, balance-chambers at each side of said cylinder inclosing the ends of the abutment-cylinder, grooves in said chambers partly surrounding the abutment-cylinder and terminating opposite the dead-point, packing-plates set into the periphery of the abutment-cylinder opposite the piston and engaging said grooves, and ducts leading to the opposite ends of said grooves from the respectively opposite admission and exhaust passages. 85
- 35 8. The combination, in a rotary engine, of a cylinder, a wing-piston and an abutment-cylinder rotating therein, said abutment-cylinder being divided transversely, a packing-roller provided with a slot through which the piston passes pivotally mounted in a slot formed in the halves of the abutment-cylinder, and packing-strips in the sides of the roller between the piston and the sides of the slot in the abutment-cylinder. 90
